UNITED STATES PATENT OFFICE.

STEPHEN B. MORSS, OF RAIHWAY, NEW JERSEY.

DESIGN FOR A CURB AND GUTTER BLOCK.

SPECIFICATION forming part of Design No. 33,140, dated August 28, 1900.

Application filed April 24, 1900. Serial No. 14,193. Term of patent 14 years.

To all whom it may concern:

Be it known that I, STEPHEN B. MORSS, a citizen of the United States, residing in Rahway, Union county, New Jersey, have invented and produced a new and original Design for a Curb and Gutter Block, of which the following is a specification, reference being had to the accompanying drawings, forming part hereof, wherein—

10 Figure 1 is a perspective view of a curb and gutter block embodying my design, and Fig. 2 is a similar view looking from the side opposite that shown in Fig. 1.

15 As shown in the drawings, the leading or material feature of my design consists in a substantially-rectangular plate or beam provided on opposite sides and near opposite edges, respectively, with outwardly-extending longitudinally-disposed webs, each web 20 being located at a distance from the adjacent edge of the plate or beam, part of the material of the plate extending above the upper web and part below the lower web.

The letter A indicates a substantially-rec-

tangular plate or beam which is of greater 25 length than height and provided on one side with an outwardly-projecting web B, which extends longitudinally of the plate or beam and is disposed at substantially right angles thereto, being located at a short distance below the upper edge a. From the opposite side of plate or beam A a web C extends longitudinally thereof and projects outwardly at substantially right angles to the plate, and said web is located at a distance above the 30 lower edge b. Beneath the web B one face of plate or beam A is plane, and above the web C the opposite face of the plate or beam is also plane.

Having described my invention, what I 35 claim as new, and desire to procure by Letters Patent, is—

The design for a curb and gutter block, substantially as shown and described.

STEPHEN B. MORSS.
